MAGAZINE RACK

Carl G. Anderson, Rte. 1, Box 15, Wausa, Nebr.

Filed Nov. 22, 1963, Ser. No. 77,580

Term of patent 14 years

(Cl. D33—2)

Fig.1

Fig.3

FIG. 1 is a perspective view of a magazine rack from the front, showing my new design;

FIG. 2 is a perspective view from one side, and

FIG. 3 is a perspective view partially from the rear.

The side of the magazine rack not shown in the drawing is plain and unornamented.

I claim:

The ornamental design for a magazine rack, as shown and described.
